UNITED STATES PATENT OFFICE.

ANDREW LITTLE, OF NEW YORK, N. Y.

DESIGN FOR A FONT OF PRINTING-TYPE.

SPECIFICATION forming part of Design No. 12,192, dated March 22, 1881.

Application filed February 5, 1881. Term of patent 14 years.

To all whom it may concern:

Be it known that I, ANDREW LITTLE, of the city, county, and State of New York, have invented and produced a new and original Design for a Font of Printing-Type, of which the following is a specification.

The nature of my design is clearly shown in the accompanying typographic impression, to which reference is made; and it consists of a design for a font of Script printing-type, the distinguishing characteristic of which is found in the looped termination placed upon the left of the letters A, B, D, F, I, M, N, P, R, T, U, V, W, and Y; upon the right of the letters C, E, G, J, L; upon both the right and left of the letters H, K, S, X, and Z, and about the central upper portions of the O and Q, and in the tail of the latter. The lower termination of the letter J and symbol & upon the left is flattened out and curved to the right. The looped

ornamentation is found in the symbol & upon the right at the bottom.

The design is preserved in the lower-case and figures: upon the right of the letters c, f, k, and t; upon the left of the v, w, and z; upon both terminations of the s and x, and about centrally in the upper part of the o; in the figures 3, 5, and 9, upon the left; upon the right of the 6, and at about the center of the upper portion of the 0. The dollar-mark symbol has both terminations partly looped.

Having now described my invention, I claim as new—

The design for a font of printing-type, as shown and described.

ANDREW LITTLE.

In presence of—

WILLIAM V. H. HICKS,
A. SIDNEY DOANE.
